UNITED STATES PATENT OFFICE

MARY D. NEILSON, OF MINNEAPOLIS, MINNESOTA

UNDERGARMENT FOR WOMEN

Application filed April 20, 1927. Serial No. 185,167.

My invention relates to undergarments for women particularly that type of undergarment known as a slip. It is the object of my invention to provide such an undergarment which shall be exceedingly simple in construction, can be cut with a large degree of economy from the average width of material, will fit the wearer in such wise as to hang properly, be comfortable in use and yet 10 which provides expansibility of the lower part so as to give perfect freedom of movement when the garment is worn. It is essential for a slip to be worn with the dress of the prevailing type to hang straight enveloping the form of the wearer in a sheath-like manner. At the same time it is desirable to provide such a garment which can expand at its lower portion in walking or other movements of the limbs or body of the wearer. 15

20 In attaining the desired results I fabricate the garment with a single front member running the full length of the garment, to which are connected along the lower part of the sides of the front symmetrically-disposed back portions of equal size, the upper parts overlapping one another at the waistline and being there secured together and to the upper part of the back, thus producing a skirt portion adapted to expand at its bottom and 25 providing a double fold of material at the back advantageously worn under thin fabric outer garments.

The upper part of the garment may be provided with side openings permitting the same 30 to be expanded for ease in slipping on over the shoulders of the wearer.

The slip is also provided with loop fastener devices secured at the upper margin of the garment at the base of the shoulder straps, 35 which loops are adapted to be fastened around the shoulder straps of other garments being worn, holding all of them positioned together.

The full objects and advantages of my invention are fully described in detail herein-after and the novel features thereof are particularly pointed out in the claim.

In the drawings, which illustrate a practical embodiment of my invention,

50 Fig. 1 shows the garment as worn, in posi-

tion upon an erect figure with the straps and loops exposed. Fig. 2 shows the position of the garment as worn, when one of the limbs of the wearer is raised. Fig. 3 illustrates the pattern of the complete garment ready to be 55 united by sewing or otherwise. Fig. 4 is a detail view of the shoulder loop straps. Fig. 5 illustrates the economical method of cutting the garment from material as it ordinarily comes from the loom. 60

As illustrated, the front member 10 of the garment comprises a single piece which when fabricated will extend from the strap supports above the bust line straight down to the bottom of the garment. 11 and 12 are pieces 65 or portions forming the lower part of the back of the garment. In practice, as illustrated in Fig. 5, these pieces will be cut from the goods integral with the central front portion 10. They may, however, be separately 70 cut from the goods and united with the member 10 as indicated in dotted lines at 13 in Fig. 3. An upper back member 14 is provided which is sewed along its longer lower edge 15 to the overlapped upper edges 16, 17 of the 75 bottom back members 11, 12. The edge 15 is slightly longer than either edge 16 or 17, which are not completely overlapped but only sufficiently to make the length of their combined edge equal to the edge 15. The edges 18, 80 19 of the upper back member are then sewed to the edges 20, 21 of the upper front member, which edges are made of the same length by 85 means of darts 22, 23 in the upper front portion of member 10. As clearly shown in Fig. 3, the edges 20 and 21 of the front converge upwardly from a point about at the hip line of the garment and the edges 18 and 19 of the back member 14 likewise converge upwardly. 90 This upper back member is, however, smaller than the upper portion of the front member having the converging lines. Also, the line of union between the edges 15 and 16, 17 will be at a point approximately at the hip line of the garment. If desired the seams along edges 18, 20 and 19, 21 may be left open a desired distance as indicated at 24 to be secured in final position by means of snaps or other 95 fasteners 25. Shoulder straps 26, 27 are secured to the upper margins of the front and 100

back portions as indicated at 28 and 29, respectively. At the point of securing the shoulder straps to the upper margin of the garment loops 30 are provided, sewed or otherwise permanently secured at one end and adapted to be removably secured at the other end by means of snaps or other fasteners 31. By this means, as clearly shown in Figs. 1 and 2, the straps 32 of other undergarments may be secured to the slip, thus holding all the straps together, preventing the tendency to separate and keeping the upper edges of all of the undergarments as worn similarly positioned.

The advantages of the slip undergarment above described will be apparent from the foregoing description. There is exceeding simplicity. In practice, but two pieces are employed for the entire garment, aside from shoulder straps, and these are cut at a minimum expense and with practically no waste at all, as is shown in Fig. 5. The garment hangs unusually well. It has the sheath form so desirable for present modes of dress, and yet it gives perfect freedom of action of the limbs and provides a double, straight-hanging, non-wrinkling fabric at the back of the garment.

I claim:

An undergarment slip for women comprising a single front piece having upwardly-converging upper side edges and substantially parallel lower side edges; an upper back piece narrower in width than the upper portion of the front piece with correspondingly converging side edges sewed to the upper side edges of the front piece and extending to a point substantially at the hip line of the wearer, and a pair of lower back pieces each having an edge connected with a lower side edge of the front piece and being sewed along their parallel upper edges in overlapping relation to the lower edge of the upper back piece.

In testimony whereof I hereunto affix my signature.

MARY D. NEILSON.
